UNITED STATES PATENT OFFICE.

HENRY TSCHERNING, OF FREEPORT, ILLINOIS, ASSIGNOR TO ARCADE MANUFACTURING COMPANY, OF FREEPORT, ILLINOIS, A CORPORATION OF ILLINOIS.

SAND-MOLDING APPARATUS.

1,216,750.

Specification of Letters Patent. Patented Feb. 20, 1917.

Application filed October 6, 1916. Serial No. 124,030.

To all whom it may concern:

Be it known that I, HENRY TSCHERNING, a citizen of the United States, and resident of Freeport, in the county of Stephenson and State of Illinois, have invented certain new and useful Improvements in Sand-Molding Apparatus, of which the following is a specification, reference being had therein to the accompanying drawing.

- 10 In certain "rock-over" sand molding apparatus it is common to place a pattern board and flask upon a plate or table adapted to rest upon a jarring support, and to secure this plate to the rock-over frame by 15 which the filled flask is inverted. The table is secured to the frame by devices which in one condition allow the plate and supported flask to be vibrated vertically or jarred as if free from the frame and which in another 20 condition bind the plate firmly to the frame.

This invention pertains to securing devices adapted to pass automatically, at proper times, from one condition to the other, so that the operator may rapidly 25 form molds, invert them, remove the pattern, and return the parts to initial position ready for forming another mold, all without considering locking and unlocking. By these means the daily output is materially increased, and at the same time strain, 30 fatigue and liability to errors are decreased.

In the accompanying drawings:

Figure 1 is a side elevation of a portion of a sand molding machine provided with 35 my devices.

Fig. 2 is a plan view partly in section of a rock-over frame.

Figs. 3, 4 are detail views partly in section of certain table locking devices.

Fig. 5 is a sectional view showing in detail an air connection, without novelty, seen in Figs. 1 and 3.

In these figures, 5 represents a base having between its ends a standard 6 and on opposite sides of the standard, respectively, a jarring device 7 and a mold support 8. A normally horizontal plate or frame 9 is centrally cut away to drop over the upper portion of the jarring device and is provided with inclined arms which are pivoted in the standard to swing approximately 180° about an axis 10 to bring the frame again to horizontal position above the support 8 where it is arrested by the top of the standard 6. 55 Above the frame 9 when it surrounds the

jarring device is a plate or table 10' which may rest upon the jarring device and vibrate vertically therewith and which may also be firmly clamped to the frame, automatically, when the frame rises. To provide for this, four bolts 11 depending from the table fit rather closely, and yet slide freely, in vertical holes in the frame. The two bolts on the same side of the machine are connected at some distance below the frame by a rigid bar 12 the ends of which are held between nuts 13 and the middle part of which is provided above with an inclined face 14. Between the bolts of each pair a small power cylinder 15 is fixed to the frame with its piston rod 16 sliding in a bearing 17, and to the piston rod is fixed a block 18 arranged to strike the inclined face 14 and push the bar 12 aside, when the piston and rod are forced in the proper direction, thereby pulling the rods in their ways in the frame and drawing the table firmly against the latter and practically locking the two together. That the parts may be unlocked when in position for jarring and may be automatically locked when they pass from that position, I provide a spring for holding the parts locked and provide for shifting to unlocked condition when the frame swings down to position for jarring. A convenient construction is illustrated, 75 fluid under pressure being brought through hose pipes 19 to T unions 20 in one end of each of which is secured a hollow rod 21 through which air passes to a slide valve device 22 governing the admission of air to the corresponding cylinder, while in the other end of the head of the T is fixed an alining closed extension 23 sliding without rotation in a bearing 24, abutting against 80 the standard 6, and pushed back thereby so far as to shift the slide valve 22 and compress a spring 25 coiled about the rod between the cylinder and a shoulder or block 26 on the rod. So long as the frame remains in jarring position its weight holds the spring compressed and keeps the slide valve in position to prevent the fluid from pushing the piston and block 18 toward the inclined face 14, and the table, bolts, and bars are thus left free to vibrate with the 85 jarring devices.

When the table begins to swing upward, the springs force the rods outward, opening paths for the fluid to reach the opposite 90

sides of the pistons where it pushes the blocks on the piston rods over the inclined surfaces on the bolt-connecting bars, locking the table to the frame as above set forth.

5 In use, a pattern plate 30 is secured to the table, a flask 31 is placed upon the plate and filled with sand which is packed about the pattern in part, at least, by jarring. A cover is then placed upon the flask and secured to 10 the table in any suitable way. The frame is then rocked over to invert the flask above the support 8, the table which was free to vibrate independently of the frame being locked rigidly to the frame as soon as the swinging 15 of the latter begins. When the flask has been properly supported in its new position, it with its cover are freed from the table 10' and lowered gently drawing the mold from the pattern, and then the table, still locked 20 to the frame, is swung back to initial position ready to receive another flask, the table and frame having been automatically unlocked again when as the frame descended the ends of the rod-extensions 23 struck the 25 standard 6 shifting the slide valve and allowing the air to force the blocks 18 away from the surfaces 14.

It is evident that, without any attention 30 from the operator, the pattern-supporting table and flask are locked to and unlocked from the swinging frame at the proper times, the locking being by a force like that of a wedge driven by fluid under pressure.

Obviously the invention is not limited to 35 any specific air-valve arrangement nor to having the piston moved one way by a spring, nor to the exact construction in other details.

What I claim is:

40 1. In sand jarring machines for molding the combination with a suitably mounted rock-over frame, of a normally horizontal pattern-supporting device secured to said frame by a series of vertical rods or bolts 45 initially allowing free limited separation of the connected parts, a fluid pressure device for acting upon the bolts simultaneously to bind the pattern supporting device rigidly to the frame, and means whereby the weight 50 of the frame and its load holds said fluid pressure device out of action while the parts are in position for jarring.

2. In sand molding apparatus, the combination with jarring mechanism, of a rigid 55 standard and a sand jarring device alongside the standard, a pattern plate and flask carrying frame pivoted to the standard to swing the plate and flask to and from position upon the jarring device, pneumatically operated means for locking said plate and frame rigidly together, and a gravity actuated member carried by the frame and holding said means out of action only while the frame is in jarring position.

60 3. In sand molding apparatus, the com-

bination with a jarring mechanism and a standard alongside the same, of a rock-over frame adapted to swing a pattern support and flask to and from position upon said jarring mechanism, pneumatic means for rigidly locking together the frame and pattern support, a movable member controlling said means, mounted upon said frame in position to be pressed against said standard by the weight of the frame when in jarring position and by consequent displacement to hold said means out of action, and a spring for restoring the displaced member to initial position.

4. In sand molding apparatus, the combination with a rock-over frame, of a pattern and flask supporting member tied to the frame by a series of bolts primarily allowing free limited separation of the frame and member, devices carried by the frame for applying wedge-like force to said bolts to draw said member rigidly against the frame, means for applying pneumatic actuating power to said devices, and means whereby gravity prevents the action of said power while the flask is in jarring position.

5. The combination with sand jarring devices and a standard alongside the same, of a rock-over frame provided with a flask support and adapted to carry a flask to and from the jarring devices, a series of vertical rods passing downward from said support through a portion of said frame, a bar connecting the lower portions of two of said rods and having an upper inclined surface, 100 a block adapted to be pushed along said surface, a fluid pressure cylinder mounted on said frame and arranged to force said block along said surface while holding it against lateral displacement thereby for binding said 105 support rigidly to said frame, and means whereby the block is kept from said surface while the parts are in position for jarring.

6. The combination with a sand jarring mechanism and a standard alongside the 110 same, of a rock-over frame pivoted to said standard, a flask support connected to the frame by vertical rods, bars on each side of the frame, respectively, connecting the lower portions of the rods upon the corresponding 115 sides, fluid pressure cylinders mounted on the sides, respectively, of the frame and arranged to force said bars laterally to pull the rods and thus bind the support to the frame, springs tending to hold the fluid pressure 120 devices in operation, and means whereby the springs are prevented from acting so long as the parts are in jarring position.

7. The combination with a standard, of a rock-over frame pivoted to the standard to 125 swing in a vertical plane, a table parallel to the frame and capable of independent vibration, a compressed fluid cylinder mounted on the frame, a piston working in the cylinder and having upon the exterior portion of its 130

rod a lateral projection, devices in the path of and operable by said projection to draw the table and frame together, a conduit for supplying fluid to the cylinder, and means whereby locating the frame in a given position prevents the specified action of the piston.

8. The combination with a jarring device, of a rock-over frame, a flask support normally located upon the upper face of said frame, a fluid pressure cylinder parallel to said support, secured to the opposite face of the frame and having on its rod a lateral projection, bolts extending from said sup-

port to a plane below the frame, a bar connecting adjacent bolts below the plane of the cylinder and having a face in and inclined to the path of said projection, a valve for admitting fluid to the cylinder to drive said projection along said face, means whereby swinging the frame to jarring position shifts the valve causing reverse movement of the piston and a spring tending to keep the valve in its normal position.

In testimony whereof I hereunto affix my signature.

HENRY TSCHERNING.
